ADJUSTABLE PEEP SIGHT FOR FIREARMS

Thomas R. Arden, Baldwin, N. Y.

Application November 25, 1935, Serial No. 51,426

4 Claims. (Cl. 33—53)

This invention relates to improvements in adjustable peep-sights for firearms.

One object of this invention is to provide an improved adjustable peep-sight for firearms 5 adapted to provide different size peep-sight openings while maintaining, with certainty, a constant single axis of the various size sight-openings.

Another object of this invention is to provide an improved adjustable peep-sight adapted to be 10 adjusted smoothly and continuously from the largest to the smallest size of opening, and vice versa, without the necessity of any sudden variations in sizes of openings.

Another object of this invention is to provide 15 an improved peep-sight formed of simple elements readily manufactured and readily assembled to produce a durable efficient construction at minimum cost.

With the above and other objects in view, this 20 invention includes all improvements over the prior art which are disclosed in this application.

In the accompanying drawings, in which one way of carrying out the invention is shown for 25 illustrative purposes:

Fig. 1 is a side elevation of a gun-receiver having 25 a peep-sight made in accordance with this invention, mounted thereon;

Fig. 2 is an enlarged rear elevation of the improved peep-sight taken from the left end of 30 Fig. 1;

Fig. 3 is mainly a rear elevation with the flange of the operating-ring in central transverse section;

Fig. 4 is a view similar to Fig. 3, but with the flange of one of the cup-like operating-disks also 35 in section, the iris-leaves and other parts being in elevation;

Fig. 5 is a view similar to Fig. 4, but with the sight adjusted to maximum open position;

Fig. 6 is an enlarged sectional view on line 6—6 40 of Fig. 2;

Fig. 7 is an enlarged sectional view on line 7—7 of Fig. 2;

Fig. 8 is a perspective view of the peep-sight 45 body;

Fig. 9 is a perspective view of the operating ring;

Fig. 10 is a perspective view of one of the operating-disks;

Fig. 11 is a perspective view of the other operating-disk; and

Fig. 12 is a perspective view of one of the iris-leaves.

In the description and claims, the various parts 55 are identified by specific names for convenience,

but they are intended to be as generic in their application as the prior art will permit.

Referring to the drawings, the firearm-receiver 20 has a sight-support, generally designated by the numeral 21, and upstanding from one side of 5 the firearm-receiver as indicated in Fig. 1. Carried by the sight-support 21 is a cross-bar 22, in which is adjustably mounted a cross-slide 23 having an internally-threaded opening 24. The peep-sight 25 includes a body-member 26 including a boss 27 and an externally-threaded tubular stem 28, which threadedly engages in the threaded opening 24, with the stop-shoulder 29 of the boss 27 engaged against the cross-bar 22. The body-member 26 and the tubular stem 28 10 have a sight-passage or sight-opening 30 extending therethrough and the body-member has an enlarged annular flange 31 provided with diagonally-opposite slots 32 and 33.

34 is a peep-sight assembled unit consisting of 20 two interfitting, shallow, cup-like operating-disks 35 and 36 with six leaves 37 forming an iris and located between the disks 35 and 36. The disk 35 has a central sight-aperture or opening 38 and six operating-slots 39 extending through the disk. 25 The disk 36 has a central sight-aperture or opening 40 and six operating-slots 41 extending through the disk. The disk 36 also has two diagonally-opposite arcuate slots 42 and 43.

It will be noted that the slots 41 of disk 36 are 30 approximately radial, while the slots 39 of the disk 35 are arranged approximately at right angles to radial and to the slots 41. Each iris-leaf 37 (Fig. 12) is formed of thin sheet-metal of 35 elongated form and has one end 44 bent transversely approximately at right angles to the body of the leaf, and has the other end 45 bent transversely of the body in the opposite direction approximately at right angles to the body of the leaf and approximately at right angles to the 40 other bent end 44.

In forming the peep-sight unit 34, six leaves may be placed in the disk 36 with the bent ends 44 of the leaves extending through the operating-openings or slots 41 and with the bent ends 45 45 arranged in position to register with operating-openings or slots 39 of disk 35. Thereupon, the disk 35 is brought into position to cause the slots 39 to engage over the bent ends 45 and with the annular flange 46 of disk 35 fitting within 50 the annular flange 47 of disk 36, and with the lugs 48 and 49 (occupying their dotted-line positions 48^a, 49^a) of disk 35 extending through the arcuate slots 42 and 43, whereupon the lugs 48 and 49 are bent from their dotted-line positions 55

48^a and 49^a to their full-line positions 48 and 49, thus holding the two disks 35 and 36 and the six leaves 37 all assembled together as a unit. The assembled unit can then be assembled in the complete peep-sight by engaging the lugs 50, 51 of the disk 36 in the slots 32, 33 in the flange 31 of the body-member 26. The operating-ring 52 preferably has its outer surface knurled and is provided with interior slots 53, 54 and a sight-aperture or opening 55. The operating-ring 52 is assembled over the flange 31 of the body-member 26 and rotated until the slots 53 and 54 engage with the lugs 48 and 49 of disk 35. Or, the unit 34 can be assembled in the peep-sight 15 in reverse position with the lugs 50, 51 in the slots 53, 54 and with the lugs 48, 49 in the slots 32, 33. The surface 56 of the operating-ring engages against the end face of flange 31 to limit the telescopic engagement of the parts 52 and 31 20 to form a bearing surface for the relative rotation of them. The annular edge 57 of the operating-ring 52 is spun or flanged over into contact with the chamfered surface 58 of the body-member 26 to hold parts 52 and 26 in assembled rotary 25 relation.

When the operating-ring 52 is rotated anti-clockwise, the iris-leaves are caused to swing toward the axis of the sight-opening to provide the smallest opening to which the sight can be adjusted, such, for example, as is illustrated in Figs. 2, 3, and 4. When the operating-ring 52 is rotated clockwise, the leaves 37 are caused to swing outwardly away from the axis of the sight-opening to their maximum open position, such as 35 illustrated in Fig. 5.

It will thus be seen that a peep-sight constructed in accordance with this invention permits of readily varying the sight-opening slowly or quickly and continuously to any desired size 40 of opening within its range of adjustment, and without shifting the axis of the opening. In other words, this sight can be adjusted from the smallest to the largest opening while the person is looking through the sight, and without obstructing sight through the sight-passage.

The device may be made of any suitable materials and the disks and leaves will preferably be made of non-rusting material, such, for example, as sheet-brass or other suitable non-rusting 50 sheet-material. An embodiment of the peep-sight illustrated in the drawings has been constructed with the operating-ring of $\frac{5}{8}$ " outside diameter and with the leaves made of sheet-metal having a thickness of between .005" and .006". This peep-sight can be adjusted to give a sight-opening considerably smaller than $\frac{3}{2}$ " diameter.

The invention may be carried out in other specific ways than that herein set forth without departing from the spirit and essential characteristics of the invention, and the present embodiment is therefore to be considered in all respects as illustrative and not restrictive, and all changes coming within the meaning and 65 equivalency range of the appended claims are intended to be embraced therein.

I claim:

1. An adjustable peep-sight construction for firearms comprising: a pair of interfitting cup-like operating-disks assembled together with their

cup-openings toward each other for limited rotation relative to one another on a common axis and each disk having a sight-opening coaxial of said common axis and a plurality of operating-openings spaced concentrically about the axis of 5 the sight-openings; a plurality of elongated leaves between said disks and arranged in overlapping relation about the axis of the sight-openings; each leaf having one end bent transversely of its body and engaged with a respective operating-opening of one disk, and the other end bent transversely of its body in the opposite direction and engaged with a respective operating-opening of the other disk. 10

2. An adjustable peep-sight construction for 15 firearms comprising: a pair of operating-disks assembled together for limited rotation relative to one another on a common axis and each disk having a sight-opening coaxial of said common axis, and a plurality of operating-slots spaced 20 concentrically about the axis of the sight-openings, the slots in one disk being approximately radial of said openings and the slots in the other disk being approximately at right angles to radial; a plurality of elongated leaves between said 25 disks and arranged in overlapping relation about the axis of the sight-openings; each leaf having one end bent transversely of its body and engaged with a respective operating-slot for one disk, and the other end bent transversely of its 30 body in the opposite direction and approximately at right angles to the other bent end and engaged with a respective operating-slot of the other disk.

3. An adjustable peep-sight construction for 35 firearms comprising: a pair of sheet-metal operating-disks secured together in assembled relation for limited rotation relative to one another on a common axis by means of a pair of slots and a pair of tongues formed in the disks, and 40 the tongues interengaging with the slots; each disk having a sight-opening coaxial of said common axis, and a plurality of operating-openings spaced concentrically about the axis of the sight-openings; and a plurality of elongated leaves 45 between said disks and arranged in overlapping relation about said axis; each leaf having one end engaged with a respective operating-opening of one disk, and the other end engaged with a respective operating-opening of the other disk. 50

4. An adjustable peep-sight construction for firearms comprising: a base and a cover providing a housing-space and having coaxial sight-openings; a pair of sheet-metal operating-disks in said housing-space and secured together in 55 assembled relation for limited rotation relative to one another on a common axis with said sight-openings by means of a pair of slots and a pair of tongues formed in the disks, and the tongues interengaging with the slots; each disk 60 having a sight-opening coaxial of said common axis, and a plurality of operating-openings spaced concentrically about the axis of the sight-openings; and a plurality of elongated leaves between 65 said disks and arranged in overlapping relation about said axis; each leaf having one end engaged with a respective operating-opening of one disk, and the other end engaged with a respective operating-opening of the other disk.

THOMAS R. ARDEN. 70
